CLAIM

The ornamental design for a child bungee bouncing toy, as shown and described.

DESCRIPTION

FIG. 1 is a top perspective view of a child bungee bouncing toy showing my new design;

FIG. 2 is an exploded top perspective view thereof;

FIG. 3 is an enlarged fragmented top perspective view, the ball opened for clarity of illustration; and,

FIG. 4 is a bottom perspective view of FIG. 3.

FIGS. 3 and 4 are disclosed broken away for ease of illustration.
